UNITED STATES PATENT OFFICE.

WILLIAM FLEENOR, OF DECKERVILLE, MICHIGAN, ASSIGNOR OF ONE-THIRD TO
WALTER BUNYAN, OF DECKERVILLE, MICHIGAN.

DIFFERENTIAL-POWER-TRANSMITTING MECHANISM.

1,178,005.

Specification of Letters Patent.

Patented Apr. 4, 1916.

Application filed July 5, 1913, Serial No. 777,552. Renewed February 28, 1916. Serial No. 81,057.

To all whom it may concern:

Be it known that I, WILLIAM FLEENOR, a citizen of the United States, residing at Deckerville, in the county of Sanilac and State of Michigan, have invented a new and useful Differential-Power-Transmitting Mechanism, of which the following is a specification.

The present invention appertains to mechanisms for transmitting power, and more particularly to such mechanisms embodying differentials, or wherein the driven members may rotate with different velocities or one faster than the other.

It is the object of the present invention to provide a novel and improved mechanism of the character indicated which shall be so constructed and operated that the driving member may be actuated or rotated in either direction to move the driven members therewith, the driven members being adapted to rotate faster than the driving member irrespective of the direction in which the driving member is rotated.

This invention contemplates the production of a power transmitting mechanism for motor propelled vehicles, such as traction engines, automobiles, and the like, the driving element of the mechanism being either directly or indirectly connected to the prime mover or motor, and the driven elements being connected directly or indirectly to the respective traction wheels, in order that when the course or path is other than in a straight line, the traction wheel toward the outer side will be permitted to travel or rotate faster than the inner wheel.

The present invention has for a further object to provide a mechanism of the character specified which shall be comparatively simple, substantial, durable, compact and inexpensive in construction, as well as efficient, practical and simple in operation.

To the above and other ends, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The preferred embodiment of the inven-

tion has been illustrated in the accompanying drawings, wherein like reference characters have been employed to denote corresponding parts, and wherein:

Figure 1 is a side elevation of the mechanism. Fig. 2 is a sectional view taken on the line 2—2 of Fig. 1. Fig. 3 is an inner face view of one of the driven elements with its associate parts. Fig. 4 is a side elevation of the driving element, certain of the other parts of the mechanism being shown in dotted lines to illustrate the operation of the mechanism.

Referring specifically to the drawings, there has been provided a driving element 5 which is rotatably mounted on a shaft or axle 6. The shaft 6 is preferably stationary and supported in any suitable manner, and the driving element 5 is preferably of the form of a disk having peripheral gear teeth so that the driving element resembles or is in the form of a gear wheel to be connected either directly or indirectly with the prime mover or motor in a manner which need not be shown or described.

The driven elements have been designated by the numeral 7, the same being in the form of disks of slightly smaller diameter than the disk 5. These driven elements are preferably formed on their outer faces with integral gears 8 so that the respective driven elements may be connected either directly or indirectly with the traction wheels of the vehicle, or with any other parts to be driven, according to the use to which the mechanism is put. The driven elements are also rotatably mounted on the shaft 6, the driving element being interposed or sandwiched between the driven elements, and the whole being retained in position on the shaft by means of collars 9 on the shaft exteriorly of the driven elements. It may be mentioned at this point, that the member 5 and the members 8 may be in the form of either gears, sprockets or the like for purpose of conveniently transmitting the power, both to the driving element and from the driven elements.

The cardinal feature of the present invention resides in the operative connection between the driving and the driven elements in order that the motion of the driving element may be imparted to the driven elements, and in order that the driven elements

may rotate faster than the driving element irrespective of the direction in which the driving element is rotated, the same residing in the construction and details as presently described.

The driving element 5 is provided on each side or face with concentric enlargements or extensions 10, each of the said enlargements being provided with a plurality, in this case three, of peripheral or radial projections 11 spaced equally apart. The configurations of the projections 11 of the enlargements 10 are such as may provide shoulders at their ends for the engagement 15 of pawls carried by the driven elements as hereinbefore described.

Each of the driven elements 7 is provided with an inwardly projecting boss or hub 12 concentric therewith, and a plate 13 is mounted on each of the bosses 12 so as to frictionally contact with the inner face of the corresponding driven element. The plates 13 being mounted on the bosses 12 and frictionally contacting with the inner face 25 of the driven elements will tend to revolve or rotate with the driven elements unless otherwise restrained. The plates 13 are of approximate triangular contour, the corners being blunt, as designated by the numeral 30 14, so as to provide cams. The particular configurations of the plates 13 will depend upon the number of projections 11, the plate, in this case being triangular to provide a cam 14 for each projection 11. These plates 35 13 are also of such dimensions or proportions that their edges will be tangent to a circle of smaller diameter than the enlargements 10, and in order that the cams 14 may project beyond the projections 11, as will 40 be apparent by reference to Fig. 4.

The cam plates 13 are connected to turn or rotate in unison by means of yoke pins 15 terminally engaged through the respective cam plates and working through arcuate 45 slots 16 in the driving element 5. Thus, the driving element and the cam plates 14 have a limited swinging movement relative to each other in order that the cams 14 may swing toward one end or the other of the 50 respective projections.

A double pawl or dog 17 is pivoted to the inner face of each driven element 7, the pawls being V-shaped and being pivoted to the driven elements at their crotches so as 55 to provide a double rocking pawl to cooperate with each set of projections 11 and cams 14. The pawls 17 are of a width to overlie both the enlargements 11 and the cam plates 13, as clearly shown in Fig. 2. 60 The pawls 17 are pivoted to the driven elements at such points as to permit the cams 14 to rotate past the pawls, and to permit the respective pawls to swing toward or 65 against the enlargements 10 to engage the projections or shoulders thereof.

The operation of the mechanism is as follows:—Let it be supposed that the driving element 5 is actuated to rotate counterclockwise as seen in Fig. 4 or in the direction of the arrow. The driven elements being operatively connected to the respective traction wheels will remain passive for an instant, so that the cam plates 13 will be held back due to the drag, until the driving element 5 has turned sufficiently so that the corresponding 70 ends of the slots 16 will strike the yoke pins 15. In this event, the cam plates 13 will be rotated with the driving element, and the respective cams 14 will swing the pawls 17 clockwise so as to engage the corresponding 75 projections 11. When the respective pawls have thus been engaged with two of the projections 11, the driven elements will be rotated with the driving element in order that the vehicle may be propelled. When the 80 cam plates 13 are thus positioned, the cams 14 will project over the ends of the projections 11 away from the direction of travel or rotation of the driving element, and thus permitting either of the driven elements to 85 rotate or turn faster than the driving element, for instance, when the vehicle is steered or turned to one side or the other. Thus, when one traction wheel is rotated faster 90 than the other, the corresponding driven 95 element 7 connected thereto will be turned faster than the driving element 5, and the forward pawl, or rather the forward end of the double pawl will ride upward on the cams 14 as it approaches them so as to be 100 swung or directed away from the projections 11. The pawl is therefore prevented from engaging the projections 11 or the shoulders formed thereby when the corresponding 105 driven element is rotated faster than the driving element, and at the same time, the rear pawl or the rear end of the double pawl, will be swung toward or against the periphery of enlargement 10 behind the projections 11, in order that when the velocity of the 110 driven element decreases, the projection will swing against the rear end of the double pawl and carry the driven element with it.

Conversely, when the driven element 5 is rotated in the opposite direction, or clockwise as seen in Fig. 4, the driven elements and the cam plates 13 will remain passive until the pins 15 engage the other ends of the slots 16, in which event, the above described operation will be resumed, only in 115 the reverse direction.

From the foregoing, taken in connection with the drawings, the advantages and capabilities of the present device will be apparent to those versed in the art, and it will be noted that the objects aimed at have been carried out satisfactorily. The present device is not only applicable to motor vehicles, but may be otherwise employed as a differential power transmitting mechanism to be 120 125 130

operated in either direction and to permit the driven elements to each rotate faster than the driving element, when necessary.

Having thus described the invention, what is claimed as new is:—

1. In a power transmitting mechanism, rotary driven members, a rotary driving member therebetween, pawls pivoted to the driven members, the driving member having shoulders to be engaged by the pawls when turned in either direction, and cams having a limited swinging movement relative to the driving member so as to direct the respective pawls away from the shoulders when the driven members revolve faster than the driving member.

2. In a power transmitting mechanism, rotary driven members, a rotary driving member therebetween and having a concentric enlargement on each side, the enlargements having peripheral projections, pawls pivoted to the driven members to engage the projections when the driving member is turned in either direction, and cams disposed between the driving and driven members and having limited swinging movements relative to the driving member so as to direct the respective pawls away from the projections when the driven members revolve faster than the driving member.

3. In a power transmitting mechanism, rotary driven members, a rotary driving member therebetween, pawls pivoted to the driven members, the driving member having shoulders to be engaged by the pawls when turned in either direction, cams frictionally engaging the driven members, and yoke pins connecting the cams and working through slots in the driving member, so that the cams will direct the respective pawls away from the shoulders when the driven members revolve faster than the driving member.

4. A power transmitting mechanism, rotary driven members, a rotary driving member therebetween and having a concentric enlargement on each side, the enlargements having peripheral projections, pawls pivoted to the driven members to engage the projections when the driving member is rotated in either direction, cams frictionally engaging the driven members, and yoke pins connecting the cams and working through slots in the driving member, so that the cams will direct the respective pawls away from the projections when the driven members revolve faster than the driving member.

5. In a power transmitting mechanism, rotary driven members, a rotary driving member therebetween, double pawls pivoted to the driven members, the driving member having shoulders to be engaged by the respective pawls when turned in either direction, and cams having limited swinging

movements relative to the driving member so as to direct the respective pawls away from the shoulders when the driven members revolve faster than the driving member and so as to swing the other pawls toward the corresponding shoulders.

6. In a power transmitting mechanism, rotary driven members, a rotary driving member therebetween, double pawls pivoted to the driven members, the driving member having concentric enlargements on its sides and the enlargements having peripheral projections to be engaged by the respective pawls when the driving element is rotated in either direction, and cams disposed between the driving and driven members and having limited swinging movements relative to the driving member so as to direct the respective pawls away from the projections when the driven members revolve faster than the driving member, and so as to swing the other pawls toward the enlargements.

7. In a power transmitting mechanism, rotary driven members, a rotary driving member therebetween, double pawls pivoted to the driven members, the driving member having shoulders to be engaged by the respective pawls when turned in either direction, cams frictionally engaging the driven members, and the yoke pins connecting the cams and working through slots in the driving member, so that the cams will direct the respective pawls away from the shoulders when the driven members revolve faster than the driving member, and so as to swing the other pawls toward the corresponding shoulders.

8. In a power transmitting mechanism, rotary driven members, a rotary driving member therebetween and having a concentric enlargement on each side, the enlargements having peripheral projections, double pawls pivoted to the driven members to engage the projections when the driving member is revolved in either direction, cams frictionally engaging the driven members, and yoke pins connecting the cams and working through slots in the driving member, so that the cams will direct the respective pawls away from the projections when the driven members revolve faster than the driving member and so as to swing the other pawls toward the enlargements.

9. In a power transmitting mechanism, rotary driven members, a rotary driving member therebetween and having a concentric enlargement on each side, each enlargement having a plurality of radial projections, pawls pivoted to the driven members to engage the respective ends of the projections when the driving member is rotated in either direction, cam plates disposed between the driving and driven members, each cam plate having a plurality of cams co-

- operating with the respective projections, and yoke pins connecting the cam plates and working through slots in the driving member.
- 5 10. In a power transmitting mechanism, rotary driven members, a rotary driving member therebetween and having a concentric enlargement on each side, each enlargement having a plurality of projections, double pawls pivoted to the driven members to engage the respective ends of the projections when the driving member is turned in either direction, cam plates disposed between the driving and driven members, each cam plate having a plurality of cams coöperating with the respective projections, and yoke pins connecting the cam plates and working through the slots in the driving member.
- 10 15. In a power transmitting mechanism, rotary driven members, a rotary driving member therebetween and having shoulders to be engaged by the pawls when the driving member is rotated in either direction, and a cam plate carried by and having limited swinging movements relative to that member having the shoulders, the cam plate coöperating with the shoulders and pawls to release the latter when the driven member rotates faster than the driving member.
- 15 20. In a power transmitting mechanism, rotary driven members, a rotary driving member therebetween, means carried by each driven member for engaging the driving member when the latter is rotated in either direction, and means for throwing each of the said means out of operation when the driven members revolve faster than the driving member.
- 20 25. In a power transmitting mechanism, a shaft, rotary driven members mounted thereon, a rotary driving member mounted on the shaft between the driven members, the driving member having concentric enlargements on the sides thereof, each enlargement having a plurality of peripheral projections, double pawls pivoted to the driven members to engage the respective ends of the projections when the driving member is turned in either direction, the
- driven members having inwardly projecting bosses, cam plates mounted on the bosses, each cam plate having a plurality of cams coöperating with the respective projections, and yoke pins connecting the cam plates and working through slots in the driving member.
- 25 30. In a power transmitting mechanism, a rotary driving member, a rotary driven member, pawls pivoted to one of the said members, the other member having shoulders to be engaged by the pawls when the driving member is rotated in either direction, and a cam plate carried by and having limited swinging movements relative to that member having the shoulders, the cam plate coöperating with the shoulders and pawls to release the latter when the driven member rotates faster than the driving member.
- 30 35. In a power transmitting mechanism, a rotary driving member, a rotary driven member, double pawls pivoted to one of the said members, the other member having shoulders facing in opposite directions to be engaged by the pawls when the driving member is rotated in either direction, and a cam plate frictionally engaging that member having the pawls, and having limited movements relative to that member having the shoulders, the cam plate having cams coöperating with the respective shoulders, for the purpose set forth.
- In testimony that I claim the foregoing as my own, I have hereto affixed my signature in the presence of two witnesses.
- WILLIAM FLEENOR.
